CLAIM

The ornamental design for a dog leash, as shown and described.

DESCRIPTION

FIG. 1 shows a perspective view of a dog leash showing my new design;

FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and,

FIG. 7 shows a bottom plan view thereof.

The dog leash is shown with a symbolic break in its length. The appearance of any portion of the article between the pair of dashed, broken lines forms no part of the claimed design.
